UNITED STATES PATENT OFFICE.

CHRISTOPHER F. CODA, OF DETROIT, MICHIGAN, ASSIGNOR TO THE ART STOVE COMPANY, OF DETROIT, MICHIGAN, A CORPORATION OF MICHIGAN.

FIRE-POT.

1,091,195.

Specification of Letters Patent. Patented Mar. 24, 1914.

Application filed July 10, 1911. Serial No. 637,748.

To all whom it may concern:

Be it known that I, CHRISTOPHER F. CODA, a citizen of the United States of America, residing at Detroit, in the county of Wayne 5 and State of Michigan, have invented certain new and useful Improvements in Fire-Pots, of which the following is a specification, reference being had therein to the accompanying drawings.

10 The invention relates to fire-pots of that type in which channels are provided in the sides of the pot designed for the admission of heated air to produce smokeless combustion.

15 It is the object of the present invention to overcome certain defects enhancing any constructions heretofore used, and further to obtain a simple and inexpensive construction for manufacture as more fully herein- 20 after set forth.

In the drawings,—Figure 1 is a vertical central section through the fire-pot; Fig. 2 is a perspective view of a portion of the pot; Fig. 3 is a perspective view of the 25 slotted ring section.

To secure smokeless combustion of fuels containing a high percentage of volatile matter, it is essential to commingle the distilled gases with a proper proportion of air 30 and also to heat the gases or mixture of gases and air to a temperature at which combustion may be sustained. It is not however, desirable to pass the air through the un- 35 coked fuel as this has a tendency to form too rich a mixture to burn without smoke. I have therefore, devised a construction of fire-pot in which the air for sustaining combustion of the distilled gases is admitted to the fuel only a short distance beneath the 40 top of the pot and pre-heated. This is preferably accomplished by forming the pot with an inner ring section in the upper portion thereof spaced from the body of the pot to form an intermediate air channel and also 45 slotted for the passage of air from said channel into the fuel.

More in detail, A is the fire-pot section mounted on a suitable base B and provided with any suitable construction of grate (not 50 shown). The pot is of the usual downwardly tapering form but in its upper portion is bulged outward as indicated at C. This enlargement provides space for an inner ring section D as well as an intermediate 55 air channel E between said ring and the

outer wall. The ring D is supported in position by a series of lugs F thereon engaging corresponding bearings G on the main section of the fire-pot, and to hold these lugs and bearings in registration an interlocking 60 lug and recess is formed at one point as indicated at H.

I is an outwardly extending annular flange at the upper end of the portion C, and J is a cover ring engaging the flange I 65 and extending to the upper end of the ring D. Thus the flange I, ring J and ring D together form an upper annular air channel J' which is in communication with the intermediate air channel E between the ring 70 D and wall C.

For admission of air into the intermediate annular air channel, a chamber K is formed in front of the pot and is provided with an opening controlled by a damper L. This 75 chamber K has its inner wall formed by the fire-pot which will thus heat the air when first admitted to said chamber, while the upper end of the chamber is in communication with the upper annular air channel 80 formed beneath the cover ring J. To prevent the air from directly passing into the intermediate air channel between the ring D and portion C at the front of the fire-pot a shield M is arranged at this point which deflects the air, directing it into the upper annular channel. The ring D is preferably formed with slots N in its lower portion which divide it into a series of downwardly 85 projecting fingers and which form the admission passages for the air in the intermediate channel E to the combustion zone of 90 the fire-pot.

With the construction as described in use, when the fire is fully started within the fire 95 pot, the ring D will be heated to a comparatively high temperature by contact with the adjacent incandescent fuel. By then adjusting the damper L the proper quantity of air for sustaining smokeless combustion of the 100 distilled gases is admitted through the chamber K and then through the upper annular air channel beneath the cover ring J to the intermediate annular chamber E between the section C and ring D. Here the 105 air which has been pre-heated by passing through the chamber K is raised to a still higher temperature and is then admitted through the slots N into the burning fuel. These slots N being located comparatively 110

near the top of the fire-pot, will commingle the air with the distilled gases without passing it through the main body of the fuel and will thus avoid the too rapid distillation. 5 The construction is also one which is inexpensive to manufacture, avoiding core work and forming the complete fire pot with an air chamber and channels therein with comparatively few parts.

- 10 What I claim as my invention is:
A fire-pot, comprising a downwardly tapering main section having an annular enlargement at its upper end, an air inlet chamber formed externally of said main section, an annular section supported upon said main section and depending within said

annular enlargement, forming a continuation of the inner face of said downwardly tapering main section and providing an intermediate annular air channel for admission of air to the pot, an upper annular air channel forming a communication between said air inlet chamber and said intermediate annular channel, and a shield for preventing direct passage of air from said inlet chamber to said intermediate annular channel. 20 25

In testimony whereof I affix my signature in presence of two witnesses.

CHRISTOPHER F. CODA.
